UNITED STATES PATENT OFFICE.

RAYMOND D. WEAKLEY, OF ST. LOUIS, MISSOURI, ASSIGNEE, BY DIRECT AND MESNE ASSIGNMENTS, TO PLASTIC PRODUCTS COMPANY, OF ST. LOUIS, MISSOURI, A CORPORATION OF MISSOURI.

KEY-BASE FOR SIDE WALLS AND CEILINGS.

1,076,725.

Specification of Letters Patent.

Patented Oct. 28, 1913.

Application filed October 11, 1911. Serial No. 654,061.

To all whom it may concern:

Be it known that I, RAYMOND D. WEAKLEY, a citizen of the United States, residing at St. Louis, in the State of Missouri, have 5 invented new and useful Improvements in Key-Bases for Side Walls and Ceilings, of which the following is a specification.

This invention relates to side wall and ceiling structures for buildings and other 10 purposes and particularly to means for replacing the usual wood lath and plaster and other expensive wall organizations now commonly used.

In ordinary residences and buildings wood 15 laths are applied to the side wall studding and ceiling rafters to form a key base for the plaster usually composed of lime, sand and a bonding material, such as hair or fiber. Owing to the expensiveness of lime, 20 lime plasters have been largely replaced by Portland and other analogous cements at a materially less cost, but it has been found impracticable to apply these cements to wood laths in view of the porous condition of the 25 laths and their tendency to readily absorb water and the quick hardening characteristic of Portland cement plaster which would result in buckling the wood lath and a destruction of the cement by reason of the 30 lath pushing through the latter. There is also a great waste of the ordinary plaster when applied to a wood lath covering.

The object of this invention is to provide 35 an economical covering or key base for side walls and ceilings of buildings to which cement plasters or reinforced concrete constructions may be directly applied and positively held with firmness at a materially less cost than the wood lath coverings and usual 40 lime plaster compositions, and with this object in view the invention essentially consists in the use of corrugated paper which is rendered water-proof by any suitable means and capable of being quickly applied 45 to studding and rafters and having plaster holding or key accessories forming a part thereof.

The invention further consists of a corrugated sheeting or covering of any desirable width wherein the corrugations form reinforcing means in one direction com-

bined with counter-reinforcing means at an angle to the corrugations, the latter and the counter-reinforcing means providing a key base for receiving and positively holding 55 cement plaster thereon.

The invention still further consists in the details of construction and arrangement of the several parts which will be more fully hereinafter described and claimed in the 60 preferred form.

In the drawings: Figure 1 is a sectional side elevation of a portion of a wall embodying the improved covering or key base and showing cement plaster partially applied 65 thereto. Fig. 2 is an enlarged detail side elevation of a portion of the covering or key base. Fig. 3 is a detail cross-sectional view of a portion of a wall embodying the features of the invention. Fig. 4 is a longitudinal vertical section through a part of a ceiling structure and showing the covering or key base in double form for use on extensive areas wherein the rafters or analogous devices are spaced a greater distance 70 than in the ceilings of residence buildings of ordinary construction to provide a stronger support for the greater weight of cement plaster applied to such ceilings of increased area. Fig. 5 is a detail section taken in the 75 plane of the line 5—5, Fig. 4. Fig. 6 is a detail section taken in the plane of the line 6—6, Fig. 4. Fig. 7 is a detail horizontal section of a partition structure wherein metal studs or uprights are used and showing the 80 improved covering or key base and cement plaster applied thereto. Fig. 8 is a detail elevation of a wall covering or key base of cement plaster embodying the same principle of the invention. Fig. 9 is a transverse 85 vertical section taken in the plane of the line 9—9, Fig. 8.

The numeral 5 designates a corrugated sheet which is preferably formed of paper or paper composition and comprising a 90 backing 6 as a part thereof, as clearly shown by Fig. 3. The corrugated paper as a whole is of that character well known in the market or already prepared and used for packing purposes and in making boxes or other 100 receptacles and is freely flexible so that it may be easily rolled and unrolled without

affecting the form or misshaping the corrugations. Instead of the corrugated paper as just explained, tar paper may be used and suitably corrugated by running the same 5 through or between fluted rollers. Both kinds of paper are comparatively inexpensive, but that first described embodying the backing 6 will be more largely used in carrying out the invention and will be rendered 10 water-proof by applying thereto or saturating the same with any suitable water-proofing compound or material, such for instance as paraffin, and in some instances a preservative or protective composition may be 15 applied to this paper if desired, or the paper may be otherwise treated to render it more serviceable and effective in performing its desired function in accordance with the features of this invention.

20 After the paper has been preliminarily treated or rendered water-proof a plurality of wires 7 is applied thereover by any suitable means and secured, the wires as shown extending across the corrugations in planes 25 at right angles to the latter and spaced at regular predetermined intervals, the said wires bridging the valleys between the convex portions of the corrugations, as shown by Fig. 3. These wires may be of any preferred material and gage and as one simple means of securing the same to the corrugated paper a number of finer wire loops 30 8 are threaded through the paper and twisted or connected against the wires 7 35 with the free ends projecting as at 9 to provide small keys. When the covering or key base in sheet form has been completed as just explained it is ready for use.

The invention embodying the covering 40 or key base is not limited in its scope to any precise dimensions of the paper and wire, it being understood that the dimensions may be varied at will to meet various structural contingencies and accommodate 45 different applications. For all practical purposes, however, or for general usage it is proposed to have the corrugated paper manufactured in sheets about thirty-two inches wide and several hundred feet in 50 length and the wire used will be what is known as No. 18 steel wire with the loops 55 8 applied thereover approximately every three inches on center. The covering or key base will be delivered in the market in rolls ready for application and in view of the preferred width as just specified it will cover three studs or rafters or extend 60 from the centers of the outer studs or rafters of each set of three rafters or studs, the latter being usually sixteen inches apart on center.

In applying the covering or key base to studs or rafters the one end of the sheet is secured to the floor plate or the ceiling

beam or plate, as the case may be, and 65 gradually secured by driving staples or analogous fastenings 10 over the wires 7 into the studs or rafters 11, the said staples or fastenings being driven at regular intervals between the wire loops 8. At points where 70 the studs or rafters are provided with connecting bridge strips or reinforces, similar fastenings 10 are also driven over the wires 7 and through the corrugated paper into the said strips or reinforces. The wires 7 75 are secured at their ends, as for instance by bending the same around suitable headed fastenings 12 driven into the adjacent wood structure. Where the side edges of the corrugated paper sheets are joined, an overlap 80 may be made in view of the similar construction of the corrugations, and it will be observed that at the joint two of the wires 7 are closely disposed, and when the fastening devices 10 are applied at the 85 joints over the contiguous wires 7, a very strong securement will result with material advantages in maintaining the covering or key base in applied position and in resisting the weight strain of the cement plaster 90 applied thereto. It will be seen that owing to the width of the corrugated covering or key base a large area may be very quickly sheathed therewith, and as the cost of the improved covering or key base is very materially less than the cheapest plaster holding means now used for a similar purpose, 95 the cost of construction of certain classes of residences or buildings will be correspondingly reduced without in the least impairing the necessary support for the plaster covering of walls and ceilings. In fact the improved covering or key base as herein disclosed has been found by practical test to be very much superior as a cement plaster 100 holding means as compared to the ordinary lath key base and other structures for a similar purpose. As the improved covering or key base is imperforate, the cement plaster will not be wasted by pushing through 110 the same and falling within the wall or between the opposite coverings of a wall, as is the case where a lath key base is employed.

In applying the improved covering or 115 key base to walls or ceilings having an extensive area and provided with rafters, for instance, spaced apart a considerable distance greater than in the ordinary ceiling and floor structures, the covering or sheathing is correspondingly reinforced or slightly modified to sustain the greater weight of the cement plaster applied thereto, such reinforcement or modification consisting in using two thicknesses of corrugated paper of a structure similar to that disclosed by Figs. 1, 2 and 3 and embodying 120 corrugated layers 13 and backings 14 held 125

in associated relation by wire loops 8 similar to those heretofore described which serve as fastening means for reinforce wires 7 also extending across the corrugations of the outer layer of paper, in all respects similar to the organization hereinbefore described. This reinforced form of the covering or key base is applied in the same manner as in the organization shown by Figs. 1, 2 and 3 by means of staples or fastenings 15 similar to the fastenings 10 heretofore described. This double or modified form of the covering or key base obviously has more rigidity and body strength than the single thickness of paper, and it will be seen that the backing of the outer layer is held against the corrugations of the inner or base layer.

Fig. 7 shows the invention applied to that form of partition or separating wall that is frequently used in buildings where either upright or horizontally disposed I beams 16 are used instead of the usual studs, for instance, and to opposite heads of these beams the improved covering or key base is applied to receive the plaster for the purpose of producing an intermediate partition wall at points where the studding is lacking. The two coverings or sheathings applied to the I beams 16 are held firmly in applied position by a wire 17 which is threaded through the two coverings or sheathings at intervals and extended along the opposite sides of each beam and terminally secured in a manner similar to the loops 8 hereinbefore specified. The wire 17 is given a rigid attachment to the coverings or sheathings by being carried closely over and in contact with contiguous wires 7 extending across the corrugations 5 and adjacent to the side edges of the sheets.

The wall or ceiling in either of the forms above set forth is completed by applying thereto a cement plaster covering or coating 18 which is pressed into the valleys of the corrugations and under the wires 7 or between the latter and the portions of the valleys which they cross and also over the free ends of the wire loops 8 providing the smaller keys. The cement plaster fully encloses all parts of the improved covering or key base and will be firmly and reliably held by reason of the formation of the corrugations and the relative positions of the wires 7 and 8, and though the paper should break in the course of time the plaster covering will still be firmly held by the wires. The corrugated paper has a tendency to cause the corrugations to lean to one side or in one direction and it is therefore better to have the covering or key base applied to a side wall with the corrugations pointing upwardly instead of downwardly so as to form a stronger and more positive support-

ing means for the plaster. The cement 65 plaster is applied over the covering or sheathing in the same manner as ordinary lime plaster and is generally about one-quarter of an inch thick and within four or five hours this plaster becomes thoroughly 70 set and presents a strong, solid, stony surface to receive the second and third coats of plaster. It will be observed that the wires 7 all run parallel to the studding and ceiling rafters and those wires which are 75 securely fastened to the studding or rafters create a bond between the latter and the wires running thereover so that when the plaster is applied it will be almost impossible to separate the plaster panels from the 80 studding or ceiling rafters without first breaking the wires or pulling out the fastening means engaging the same and the studding and rafters. In other words, the wall or ceiling when completed will be practically indestructible and if the plaster becomes broken by more than ordinary stress imposed thereon the steel wires will hold the plaster together and the break can be easily replastered. By means of the structure 90 hereinbefore described a fire-proof plaster is produced at a comparatively small expense and of a very durable nature.

From the foregoing description it will be understood that the underlying principle of 95 the invention is the production of a key base for holding a plaster covering or coating of a wall or ceiling, and this key base may be formed of paper with corrugations and wires intersecting the corrugations, or, 100 as shown by Figs. 8 and 9, the corrugations may be formed in a plaster or cement plaster covering or key base 19 by any suitable means, and having wires 20, similar to the wires 7 heretofore described, intersecting 105 and held by the plaster or cement corrugations and crossing the valleys between the convex portions of said corrugations to provide keys to engage and hold the outer coating or cover 21 of plaster or other analogous material applied over the corrugated 110 surface, as shown by Fig. 9. This latter construction embodies the simplified form of the invention and will be used in many wall and ceiling structures.

115

What is claimed is:

1. A covering or key base for walls and ceilings, consisting of an imperforate flat sheet having a corrugated sheet firmly secured thereon and having its corrugations 120 exteriorly exposed, the united sheets being flexible, and wires extending across and secured against the outer portions of the exteriorly exposed corrugations or the corrugated sheet at intervals to form key ways 125 with the said corrugations by bridging the valleys between the latter, the securement of the flat sheet and corrugated sheet relatively

to each other being independent of the wires extending over the corrugated sheet.

2. A covering or key base for walls and ceilings, consisting of two flexible pieces of 5 waterproof material secured to each other and having air spaces formed between them, the one piece being corrugated and having its corrugations exteriorly exposed, and wires extending across and fixed against 10 said exterior corrugations of the corrugated piece and forming key means with relation to the corrugations of the latter piece, the flexible pieces of material being continuous and having the wires extending thereover 15 solely in a longitudinal direction.

3. A covering or key base for walls and ceilings, consisting of a flexible sheet of corrugated material composed of an imperforate flat backing sheet for securement against 20 a support and a front corrugated sheet fixed to the backing sheet, the corrugated sheet having the corrugations thereof exteriorly exposed and individual strands or key 25 wires extending at an angle over and secured against the outer portions of the corrugations of the said corrugated sheet and bridging the valleys between the said corrugations, the key wires being secured at intervals to the flexible sheet throughout the 30 length of the latter and primarily fixed to the sheet before the said sheet is applied to a wall or ceiling to serve solely as key means and not as fastening means for the sheet 35 relatively to the support against which the sheet is applied.

4. A covering or key base for walls and ceilings, consisting of a flat imperforate backing sheet and a front corrugated sheet secured thereto and of a waterproof character, the sheets having elongated air spaces 40 formed between them, the corrugations of the corrugated sheet being exteriorly exposed, and key strands extending over and secured against the outer portions of the 45 said corrugations at an angle to the latter and to the air spaces and having means engaging the same throughout their length to maintain them at fixed distances apart, the key strands being independent of the securing 50 means of the sheets relatively to each other and of the means for securing the sheet against the support, the said strands being flexible and secured to the double sheet prior 55 to the application of the latter to a wall or ceiling.

5. A covering or key base for walls and ceilings, consisting of a strip of flexible material having two members primarily secured to each other, one member being corrugated 60 and having its corrugations exteriorly exposed, and key wires fixed against the outer portions of said corrugations and carried by the strip, the member having corrugations being the face member and the other mem-

ber the backing for application to a support, 65 the said key members running longitudinally of the strip at an angle to the corrugations and maintained at fixed distances apart, the key wires being independent of the securing means for the strip relatively to the support and also of the means for securing the one member to the other.

6. A key base for walls and ceilings, consisting of flexible imperforate material comprising a flat backing sheet and a front corrugated sheet secured to the backing sheet, the corrugated sheet having its corrugations exteriorly exposed, and flexible wires angularly intersecting and fixed to the material against the outer portion of the corrugations 70 of the corrugated sheet in bridging relation to the valleys between the said corrugations, the wires being maintained at fixed distances apart and secured at intervals throughout their length to the corrugated sheet at their 75 points of intersection with the corrugations.

7. A covering or key base for walls and ceilings, consisting of an imperforate piece of corrugated material comprising a flat backing sheet and a front corrugated sheet 80 secured thereto, flexible wires fixed to the piece and engaging the corrugations and disposed at an angle to the latter, a supporting structure against which the backing sheet 85 part of the piece of material is secured and the outer corrugated sheet exposed for receiving a plaster coating, securing means for the material and fastening devices applied over the wires in addition to the securing means of the latter relatively to the piece 90 of material and driven into various parts of the supporting structure.

8. A covering or key base for walls and ceilings, consisting of an imperforate piece of corrugated material comprising a flat 105 backing sheet and a front corrugated sheet secured thereto, flexible wires applied to the piece and engaging the corrugations and disposed at an angle to the latter, the wires forming key means with the corrugations, 110 fastening devices applied to the wires at intervals and secured to the piece of material to hold the wires in place on the material, a supporting structure, securing means for attaching the piece of material and the 115 wires to the supporting structure, and fastening devices applied over the wires at intervals and driven into various parts of the supporting structure, the ends of the devices for fastening the wires to the piece of 120 material being exposed and shaped to form additional key means.

9. As an improved article of manufacture, a key base for a plaster covering consisting of a flexible sheet of material embodying an 125 imperforate flat backing lamina and a corrugated lamina secured thereon to form air spaces between the laminae and to provide

an outer exposed plaster receiving corrugated surface and wires disposed at an angle and secured in fixed spaced relation to the outer portions of the corrugations and held intact with the sheet at all times, the sheet being adapted to be rolled and unrolled without disorganizing the wires and corrugations.

In testimony whereof I have hereunto set my hand in presence of two subscribing witnesses. 10
